UNITED STATES PATENT OFFICE

LOUIS H. THULLEN, OF EAST ORANGE, NEW JERSEY

DRILLING APPARATUS AND THE LIKE

Application filed November 29, 1926. Serial No. 151,305.

My invention relates to improvements in drilling apparatus and the like and more particularly to an apparatus for drilling oil wells or earth boring apparatus, although my invention may be used in many other and entirely different types of apparatus where it is desired to control the feed of a work member with respect to its work in accordance with the load imposed upon or 10 resistance encountered by the work member. The main object of the invention is to provide an arrangement in which the feeding of the drill or work member with respect to its work is automatically controlled responsive 15 to variations in the load imposed thereon or the resistance met thereby whereby a more satisfactory and even and efficient operation of the apparatus is obtained.

Further and more specific objects, features 20 and advantages will more clearly appear from the detail description given below taken in connection with the accompanying drawings which form a part of this specification.

In the drawings, Fig. 1 is a view more or 25 less diagrammatical illustrating certain portions of an apparatus embodying my invention in one form. Fig. 2 is an elevation taken substantially on the line 2—2 of Fig. 1. Fig. 3 is a view similar to Fig. 1 but 30 illustrating a modified form of apparatus. Fig. 4 is a sectional detail illustrating one method of conducting the operating fluid to and from the rotating apparatus. Fig. 5 is a section taken substantially on the line 5—5 35 of Fig. 3. Fig. 6 is a longitudinal section of parts shown in Fig. 5. Fig. 7 is a face view, partly in section, of the disc 11, cylinders 12 and parts 13, 14 and 15 of Fig. 1.

Referring to Figs. 1 and 2, 6 represents a 40 suitable steam engine or other prime mover driving a sprocket wheel 7 cooperating with a sprocket chain 8 driving a sprocket 9 keyed to the shaft 10 so that the engine will drive the shaft 10. On one end of the shaft 10 is a disc member 11 having rigidly secured thereto cylinders 12 containing suitable pistons and inlet valves 12a communicating with the outside atmosphere and outlet valves 12b communicating with a passage in the disc 11 described hereinafter. To the pis-

tons are pivotally connected piston rods 13 suitably connected with respect to a crank arm 14 on a shaft 15. The piston rods 13 are pivotally connected to their respective pistons in the cylinders 12 in any well known 55 or suitable manner, so that if the disk 11 and cylinders 12 be held stationary and the shaft 15 rotated, the crank 14 will operate the piston rods 13 to reciprocate their respective pistons in the cylinders 12, and the pistons 60 will likewise be reciprocated if the shaft 15 and crank 14 be held stationary and the disk 11 and cylinders 12 be rotated with respect thereto. Likewise the pistons will be reciprocated in their cylinders if the disk 11 be 65 rotated and the shaft 15 also be rotating, but at less speed than that of the disk 11. Suitable bearings are provided for shaft 10 as at 70 16 and suitable bearings are provided for shaft 15 as at 17. Mounted to rotate freely 70 on shaft 15 is a sprocket 18 which is adapted to be connected to be rotated by the shaft 15 by operation of a sliding clutch member 19. The sprocket 18 drives a sprocket chain 20 passing over a sprocket 21 on a shaft 22 75 which has secured thereto a bevelled gear meshing with a bevelled gear 23 on the underneath side of a rotary table member 24. The rotary table member 24 is so constructed as to provide a square aperture or hole 25 80 therein through which extends one section 26 of a drilling member, said section being square in cross-section so as to substantially fit the square opening 25 whereby rotation of the table 24 rotates the section 26 of the 85 drilling member. Suitably connected to the section 26 are other sections 27 of the drilling member, which extend into the hole or well being drilled in the ground when the apparatus is used, for example, for 90 drilling oil wells.

28 represents another shaft having bearings at 29. Secured to and rotated by a shaft 28 is a drum 30 on which is adapted to be wound a rope or cable 31 (see Fig. 2) which 95 cable passes around pulleys 32 and 33, the latter being connected by hook mechanism 34 and link 35 to the top section of the rotary drilling member in a manner well understood by those skilled in the art, the top part 36 100

of the drilling member being connected so as to raise and lower the other sections of the drilling member but remaining stationary with respect thereto as the latter is 5 involved or rotated by the table 24. A suitable water connection is shown at 37 through which water may be forced down the drilling member for purposes well understood by those skilled in the art.

10 The shaft 28 may be rotated at one speed by means of a sprocket 38 keyed to the shaft 10, operating the sprocket chain 39 passing over a sprocket 40 loose on the shaft 28 but adapted to be connected to rotate shaft 28 by 15 clutch member 41. If it is desired to rotate the drum 30 from the shaft 10 but at a different speed, this may be accomplished by sprocket 42 keyed on the shaft 10, operating sprocket chain 43 passing over sprocket 44 20 loosely mounted on shaft 28 but adapted to be connected to rotate shaft 28 by clutch member 45. As so far described, the parts, except the parts 11, 12, 13 and 14, are well known and their operation well understood, 25 that is, assuming the shafts 10 and 15 to be one shaft. However, in carrying out my invention in the form described, I provide two shafts 10 and 15 and I secure to the end of shaft 10, the disc member 11 carrying the cylinders 12 in which are pistons operated by piston rods 13 connected to the crank arm 14 secured on the shaft 15. If it be assumed that the shaft 15 be held stationary and the disc 11 be rotated by the prime mover, the 30 pistons in the cylinders 12 will be operated back and forth and so caused to compress air therein, which air is drawn from the surrounding atmosphere in any suitable manner and the compressed air is forced out of the cylinders into a passageway 46 in the disc 11 and from the passageway 46 into a passage- 35 way 47 extending through the shaft 10, which passageway 47 connects with a pipe 48 ex- tending into a stationary stuffing box 49 con- 40 nected with a safety or relief valve 50. 51 represents a suitable pressure gauge for indi- 45 cating the air pressure built up by the action of the pistons in the cylinders 12. The air under pressure from the pipe 48 passes freely 50 to the pipe 52 and to a reducing valve 53 and from the reducing valve 53 a pipe 54 leads to an engine or air motor 55 which when suf- 55 ficient pressure has been built up in the pipe 54 causes operation of the engine or air motor 55 so that it will rotate the gear 56 which in turn rotates the gear 57 secured on the shaft 28, and so will rotate the drum 30 and operate upon the cable 31 to raise or tend to raise the rotary drilling tool or member. 60 It will be seen, however, that when the engine or prime mover 6 is started and there being some resistance to the rotation of the drilling tool 26 and, therefore, some resistance to the turning of shaft 15, the shaft 15 65 will remain stationary for a certain time un-

til a certain pressure has been built up within the passageways 46, 47, etc. by operation of the pistons in the cylinders 12. This pressure, however, soon builds up to a point where it acts to prevent the pistons from operating 70 in the cylinders 12 and rotation of the disc member 11 causes operation of the shaft 15 through the crank 14 and so, through sprocket 18, sprocket chain 20 and sprocket 21 and shaft 22, causes the table 24 to rotate the 75 drilling tool. As the drilling tool encounters more resistance in its work a higher pressure is automatically built up by the pistons in the cylinders 12 in order to cause a continued rotation and operation of the 80 drilling member. Should, however, the resistance offered the drilling tool or member be so great as to be likely to twist off or break the drilling member or otherwise injure the apparatus, the pressure built up by the pistons in the cylinders 12 will reach such a value that it will cause a pressure to be applied to the engine 55 through the pipe 54 sufficient to cause this engine to act on the 85 drum 30 and tend to raise the drilling tool 90 which is fed into its work by the action of gravity and so decrease of the feed of the tool responsive to such increases in the resistance offered the tool in rotation and thus decrease the resistance offered the tool against 95 rotation, thereby resulting in a uniform operation of the drilling tool and preventing injury or damage to the drilling member or other parts of the apparatus. If for any 100 reason this built up pressure should not be effective in relieving the load on the drill, the pressure built up is limited by the safety valve 50 which is set for a certain maximum pressure which permits the air thus built up 105 under pressure to escape to the outside atmosphere, thereby limiting the force which may be applied to rotate the drilling tool or member. This pressure may be so chosen that even with the drilling tool held stationary 110 in its work (as in case it should in some way become caught) the force applied in tending to rotate the tool will not be sufficient to twist it off or injure the same. In such case the shaft 15 will be held stationary but the shaft 115 10 and disc 11 will continue to be rotated by the prime mover 6 and the pistons in the cylinders 12 will continue to operate, the air being thus built up under pressure escaping through the safety valve 50 to the outside at- 120 mosphere. The reducing valve 53 may be of any suitable or well known type but is preferably one which reduces the pressure to a given percentage of the pressure applied thereto. That is, the pressure permitted thereby in the pipe 54 will be a given percentage or proportion of the pressure of the air supplied thereto through the pipe 52. Thus during normal operation the engine or air motor 55 will act to continuously tend to 125 130

raise the drilling tool or member against the action of gravity, the force so applied in opposition to gravity being responsive to and more or less proportional to the variation of pressure being built up by the pistons in cylinders 12 and responsive to and more or less proportional to the variations in the resistance or load encountered or met by the drilling tool. Should the drilling tool or member thus encounter great resistance to its rotation, the apparatus will automatically operate to tend to decrease the force with which the tool is fed into its work and so tend to decrease the resistance offered the tool to rotation until operation is brought back to normal. If the resistance offered the tool is not sufficiently decreased by partially relieving the pressure of gravity on the tool, the pressure may continue to be built up by the pistons in the cylinders 12 to such a point that the air motor 55 will actually cause the drilling tool to be raised against the action of gravity and so relieved of its work until it may again be rotated in a normal manner. When it is desired to raise the drilling tool or member entirely, this may be done directly from the shaft 10 by throwing in one or the other of the clutches 41 or 45.

Thus I am enabled to control the feed of the drilling tool or member with respect to its work in such a manner that the weight sustained by the drum 30 will remain practically constant for a given depth of hole or length of tool. As additional lengths are added to the drilling tool as the hole is drilled deeper, the setting of the reduction valve 53 may be altered or adjusted so as to produce a greater pressure in the pipe 54 with respect to the pressure in the pipe 52 and so compensate for the added weight and corresponding added effect of gravity on the drilling tool as the length and weight of the drilling tool is increased. Also the safety or relief valve 50 may be adjusted for any desired maximum pressure depending upon the size of the drilling tool and other conditions. But by adjusting the reduction valve 53 in any suitable manner as by turning the nut 60 in a manner well understood by those skilled in the art so as to adjust the force supplied by the engine or air motor 55 to correspond with the size, length and weight of drilling member, the drilling member will be fed into its work with a given uniform force except that should it encounter increased resistance to rotation, the feed thereof will be controlled so as to decrease the resistance to its rotation, thus limiting the torque which is applied to rotate the tool and this in accordance with different conditions, but in any case so that the maximum torque applied to the tool will be less than that which will twist apart the tool or do other serious injury. Should the resistance offered the tool be so great that the shaft 15 slows down or stops while the shaft

10 is continually driven by the prime mover 6, the pressure built up in the cylinders 12 will become so great that the engine or air motor 55 will actually withdraw the drilling member from its work or if the engine 55 fails to operate in this manner, the pressure built up will be limited by the safety valve 50 and so prevent the force applied to the tool from becoming so great as to prevent substantial injury. When the engine or motor 55 acts to apply greater force tending to rotate the drum 30 against the action of gravity due to the weight of the drilling member or when the drum 30 is actually rotated so as to raise the drilling tool, the pressure with which the drilling tool is applied to its work will be decreased or relieved thereby allowing the drilling tool to again freely revolve so that the pressure built up in the cylinders 12 will drop and continue to drop until it reaches such a point that it balances the load encountered by the drilling member and this decrease in pressure acts to decrease the force applied by the engine or motor 55 tending to raise the drilling tool so that gravity again operates to feed the drilling tool toward its work and the drilling tool is thus automatically again fed to its work in a way consistent with maximum efficiency. In the arrangement shown this is accomplished by the varying pressure produced in the cylinders 12 by relative rotation of the shafts 10 and 15. This pressure is indicated by the gauge 51 and by observing the gauge the operator can tell at all times the relative amount of work being done by the drilling tool.

Referring to the modification shown in Figs. 3, 4 and 5 the same drum for raising and lowering the drill is shown at 30, on the shaft 28 having bearings at 29. The shaft 28 has sprockets 40 and 44 loosely mounted thereon but adapted to be connected to rotate the shaft 28 by sliding clutch members 41 and 45 respectively. The sprockets 40 and 44 are driven by sprocket chains from sprockets 38 and 42 respectively fixed on the main driving shaft 10 having bearings at 16. The driving shaft is similar to the driving shaft 10 of Fig. 1 except that the former has no passage therethrough. The driving shaft 10 is driven by any suitable engine or prime mover through sprocket 9.

The driven shaft 15 having bearings at 17 has a sprocket 18 loosely mounted thereon but which may be connected to be driven by the shaft 15 by a sliding clutch member 19. The sprocket 18 is connected to rotate the table which rotates the drill as shown in Fig. 1.

Rigidly secured on the end of the shaft 15 is a disc 61, provided with parallel guideways 62 along which a casing 63 is adapted to slide. The casing 63 may be moved along the guideways by means of a screw 64 cooperating with a bracket 65 rigid with the disc 61. The cas-

ing 63 contains a fluid pressure pump comprising a casing 66 (see Fig. 5) having, in the particular form shown, seven cylindrical bores in which operate seven pistons 67 respectively. The pistons 67 are pivoted at their outer ends to a ring member 68 rotatable in a corresponding circular aperture in the casing 63. The cylinder casting 66 is provided with a central aperture in which the 5 end of the shaft 15 extends and the casting 66 is rigidly connected to the shaft 10 to be rotated thereby. The shaft 15 has two segments cut therefrom at 69 and 70 directly opposite the pistons 67 and the shaft 15 is 10 provided with longitudinal passages 71 and 72 communicating respectively with the spaces 69 and 70. The shafts 10 and 15 are journaled about the same axis but the casing 63 is adjusted by the screw 64 so that the 15 center of the ring 68 is eccentric thereto as shown in Fig. 5. If, with such an arrangement the shaft 15 be held relatively stationary and the passage 71 be connected to an oil or other fluid supply and the casting 66 be 20 rotated by the shaft 10 relatively to the shaft 15, the pistons and their cylinders will be rotated with respect to shaft 15 and segment spaces 69 and 70, thereby causing the pistons to operate back and forth in their respective 25 cylinders and draw in oil or other fluid through the passage 71 and force the same out through passage 72. The construction and mode of operation of such a fluid pump is well known so that further description there- 30 of is unnecessary.

The outer end of the shaft 15 is extended into a stationary stuffing box 73 wherein suitable connection is made between the outlet passage 72 and a pipe connection 74, the passage 72 always communicating with the latter, even when the shaft 15 is rotating with respect thereto. The pipe 74 is provided with a pressure gauge 79 for indicating the pressure of the oil or other fluid in the pipe 74. 40 Communicating with the inlet passage 71 is a pipe section 75 screwed into the end of shaft 15 as shown in Fig. 4 and this pipe section 75 extends into a stuffing box 76 on a pipe 77 leading to an oil supply tank 78 or other 45 fluid supply.

The pipe 74 leads to a safety or pressure relief valve 80. If the pressure of the fluid in pipe 74 exceeds the predetermined value for which the valve is set, which value may 55 be adjusted from time to time as desired, the relief valve will permit the escape of fluid therefrom into the pipe 81 whence it flows back into the supply tank 78, and so prevent the pressure in the pipe 74 from exceeding 60 the predetermined value for which the valve is set. The pipe 74 is always in open communication with a pipe 82 so that the fluid is forced under pressure from pipe 74 into pipe 82 and the pressure of the fluid in pipe 65 82 will always be the same as the pressure of

the fluid in pipe 74. The pipe 82 leads to a pressure reducing valve 83, which may operate substantially the same as the pressure reducing valve 53 of Fig. 1, and deliver fluid at a proportionally lower pressure to the pipe 70 84. The pipe 84 leads to the intake of a fluid, or hydraulic motor 85 of any well known or suitable kind. If desired the motor 85 may be of the type shown in my copending application Ser. No. 151,306 filed Nov. 29, 1926. 75 The spent or exhaust fluid from the motor is conducted by a pipe 86 back to the fluid supply tank 78. I preferably employ a fluid motor 85 having means such as a shaft at 87 which may be turned to vary the stroke of the 80 motor so that the torque exerted by the motor may be varied with any given pressure of the operating fluid supplied to the motor. The motor 85, when operated by the fluid under pressure from the pipe 84, operates on the 85 gear 88 which meshes with the gear 57 and so acts on the drum 30 as described in connection with Figs. 1 and 2.

The function and mode of operation of the apparatus illustrated in Figs. 3, 4 and 5 is substantially the same as that of Figs. 1 and 2 except that instead of operating with air pressure it is designed to operate with liquid, such as oil, under pressure. Thus the drill or work member is driven by shaft 15 and the 90 load thereon will cause the shaft 15 to lag behind the driving shaft 10 until the hydraulic pump in casing 63 builds up a fluid pressure in pipes 74, 82, etc., sufficient to cause the shaft 15 to be driven at the desired speed 95 under normal conditions. If the load on the shaft 15 becomes excessive there will be a further rotation of the shaft 10 relative to the shaft 15 causing a greater pressure to be built up in the pipes 74, 82 and 84 and so 100 causing the fluid motor 85 to exert a greater torque tending to lift the drill against the action of gravity and so decrease the load on the shaft 15. If the load on the shaft 15 should increase to much greater value, the 105 pressure may increase to such a value as to cause the motor 85 to actually raise the drill and if this should not decrease the load on the drill the safety or relief valve 80 will permit the escape of fluid back to the tank 78 and so 110 limit the force which will be applied to the drill to a value which will not prove injurious. The torque applied by the fluid motor 85 to the drum 30 for any given pressure in pipe 84, may be varied and adjusted independently of the power applied to operate the motor while the motor is in operation, by 115 adjusting shaft 87 so as to change the stroke of the motor so that when the size of the drilling tool is increased or the length of the tool is increased as the well is drilled deeper, sufficient torque may be applied to the drum 30 to compensate for such increases in the weight of the tool. This torque may 120 also be varied to adjust the pressure with 125

which the tool is fed into its work to meet different conditions in the work. Likewise the torque exerted by the shaft 15 may be varied and the pressure produced in the pipes 74, 82 and 84 for any given load on the tool may be varied for similar purposes, by adjusting the screw 64. Any suitable arrangement may be provided for adjusting the screw 64 while the disc 61 is rotating and the apparatus is in operation.

The various parts in the various drawings are not all drawn to the same scale and the drawings are in many respects merely diagrammatical in order that the invention may be more clearly illustrated.

While I have described my improvements in connection with drilling apparatus and more particularly in connection with oil well drilling apparatus, it will be obvious that many changes and modifications may be made and the invention embodied in widely different forms and kinds of apparatus, without departing from the spirit and scope of the invention in its broader aspects. Thus the invention in its broader aspects may be embodied in any kind of apparatus where it is desirous of limiting the torque or force impressed upon tool, shaft or other work member, and particularly where it is desired to regulate or control the feed of a tool or its work, either relative to the other, and in either direction, responsive to variations in the resistance offered the tool or the load applied to the member. By adjusting the reducing valves 53 and 83 for different values, or adopting different kinds of reducing valves, the control or regulation of the feed responsive to the load variations may be widely varied as desired.

In oil well drilling apparatus such as is frequently employed the cutting tool or drilling element is quite heavy and may vary in weight from 300 lbs. to possibly 300,000 lbs. depending on the size and depth of well or hole that is being drilled. Thus when the hole reaches a considerable depth the weight of the various sections of the rotating drilling element becomes very great and the power required to rotate the drilling element, if this weight is not largely relieved, will be very great, and more than sufficient to twist the tool apart, with resultant great damage and in some cases necessitating an abandonment of the well being drilled. But by the use of my invention in its preferred form a varying force or torque is automatically applied to the hoisting drum 30 so as to largely relieve this weight and control the feed of the tool in such a manner that the power required to rotate the tool at the normal rate will be maintained nearly constant so that the drilling is accomplished in a most speedy and efficient manner, and should conditions occur which prevent the rotation of the tool the torque applied is limited by the

safety or relief valve to a safe value and the tool is withdrawn from its work.

Since the invention in its broader aspects may be embodied in widely different forms and kinds of apparatus, I desire to cover all embodiments of any one or more of the improvements described, coming within the language or scope of any one or more of the appended claims.

What I claim as new and desire to secure by Letters Patent, is:

1. The combination of a rotary drilling member, a prime mover, means whereby operation of the prime mover builds up a fluid pressure, means whereby said fluid pressure acts to rotate the drilling member by a force proportional to said fluid pressure, and means acting to decrease the force acting to feed said member with respect to its work responsive to variations in said fluid pressure.

2. The combination of a rotary drilling member, a prime mover, means whereby operation of the prime mover builds a fluid pressure, means whereby said fluid pressure acts to rotate the drilling member and means whereby the feeding of the drilling member with respect to its work is controlled responsive to variations in said fluid pressure.

3. The combination of a rotary drilling member, a prime mover, means whereby operation of the prime mover builds up a fluid pressure, means whereby said fluid pressure acts to rotate the drilling member and means whereby the feeding of the drilling member with respect to its work is controlled responsive to variations in said fluid pressure, and means independent of the prime mover for limiting said fluid pressure.

4. The combination of a rotary work member adapted to encounter a variable resistance in its work, a prime mover, means whereby operation of the prime mover builds up a fluid pressure, means whereby said fluid pressure acts to rotate the work member and means whereby the feeding of the work member relative to its work is controlled responsive to variations in said fluid pressure.

5. The combination of a rotary work member adapted to encounter a variable resistance in its work, a prime mover, connections between the prime mover and the rotary work member whereby the prime mover may rotate the work member, said connections including fluid pressure generating means acting to build up a fluid pressure dependent upon the resistance encountered by the work member in its work, and means permitting escape of the fluid under pressure when a predetermined pressure has been reached.

6. The combination of a rotary work member adapted to encounter a variable resistance in its work, a prime mover, connections between the prime mover and the rotary work member whereby the prime mover may rotate the work member, said connections including

fluid pressure generating means acting to build up a fluid pressure dependent upon the resistance encountered by the work member in its work, and means whereby the feeding of the work member with respect to its work is controlled responsive to variations in said fluid pressure.

7. The combination of a rotary work member adapted to encounter a variable resistance in its work, a prime mover, connections between the prime mover and the rotary work member whereby the prime mover may rotate the work member, said connections including fluid pressure generating means acting to build up a fluid pressure dependent upon the resistance encountered by the work member in its work, and means whereby the feeding of the work member in its work is controlled responsive to variations in said fluid pressure, and means limiting the pressure of the fluid by permitting the escape thereof when a predetermined pressure has been reached.

8. The combination of a rotary drill member, a prime mover, connections between the prime mover and the rotary drill member whereby the prime mover may rotate the drill member, said connections including a fluid pressure generator acting to build up a fluid pressure in accordance with the load encountered by the drill member, and means substantially limiting said fluid pressure to a predetermined value to limit the force which the prime mover may apply to rotate the drill member.

9. The combination of a rotary drill member, a prime mover, connections between the prime mover and the rotary drill member whereby the prime mover may rotate the drill member, said connections including a fluid pressure generator means acting to build up a fluid pressure in accordance with the load encountered by the drill member, and means whereby increases in said fluid pressure tend to decrease the feeding of the drill member into its work.

10. The combination of a rotary drill member fed by gravity to its work, a shaft connected to drive said drill member, a prime mover, a shaft driven thereby, fluid pressure generator means connecting said shafts and acting to build up a fluid pressure in accordance with the load encountered by the drill member, and means whereby said fluid pressure acts to oppose the force of gravity in feeding the drill member to its work.

11. The combination of a rotary drill member fed by gravity to its work, a shaft connected to drive said drill member, a prime mover, a shaft driven thereby, fluid pressure generator means connecting said shafts and acting to build up a fluid pressure in accordance with the load encountered by the drill member, and means whereby said fluid pressure acts to oppose the force of gravity in

feeding the drill member to its work, and means permitting the escape of said fluid under pressure when a predetermined pressure has been reached to limit the force which may be applied to rotate the drill member.

12. The combination of a rotating shaft, a shaft adapted to be rotated thereby, means including a fluid pressure generator connecting said shafts and acting to build up a fluid pressure in accordance with the load encountered by the driven shaft, and means whereby variations in said fluid pressure tend to decrease the load encountered by said driven shaft.

13. The combination of a rotating shaft, a shaft adapted to be rotated thereby, means connecting said shafts and acting to build up a fluid pressure in accordance with the load encountered by the driven shaft, and means permitting the escape of the fluid under pressure when a predetermined pressure has been reached, to limit the force which the first shaft will apply to the driven shaft.

14. The combination of a rotary table, a drill member slidable therethrough and rotated thereby, a prime mover, a shaft rotated by the prime mover, a second shaft, means connecting said shafts including a fluid pressure generator whereby the first shaft is adapted to drive the second shaft and build up a fluid pressure varying with the load encountered by the second shaft, means whereby the second shaft rotates said table to rotate said drill member, said drill member being fed to its work by gravity, and means for decreasing the force with which said drill member is fed to its work in accordance with certain variations in said fluid pressure.

15. The combination of a rotary table, a drill member slidable therethrough and rotated thereby, a prime mover, a shaft rotated by the prime mover, a second shaft, means connecting said shafts whereby the first shaft is adapted to drive the second shaft and build up a fluid pressure varying with the load encountered by the second shaft, means whereby the second shaft rotates said table to rotate said drill member, said drill member being fed to its work by gravity, and means permitting the escape of the fluid under pressure when a predetermined pressure has been reached, to limit the force which the first shaft will apply to the driven shaft.

16. The combination of a rotary table, a drill member slidable therethrough and rotated thereby, a prime mover, a shaft rotated by the prime mover, a second shaft, means inclusive of a fluid pressure generator connecting said shafts whereby the first shaft is adapted to drive the second shaft and build up a fluid pressure varying with the load encountered by the second shaft, means whereby the second shaft rotates said table to rotate said drill member, said drill

member being fed to its work by gravity, and means permitting the escape of the fluid under pressure when a predetermined pressure has been reached, to limit the force which the first shaft will apply to the driven shaft, and means whereby certain increases in said fluid pressure act to decrease the force with which said drill member is fed to its work.

17. The combination of a work member adapted to encounter a variable resistance in its work, a prime mover, connections between the prime mover and the rotary work member whereby the prime mover may rotate the work member, said connections embodying fluid pressure generator means acting to build up a fluid pressure dependent upon the resistance encountered by the work member in its work, means for regulating the feed of the work member with respect to its work, a fluid motor controlling said last mentioned means, and connections from said fluid under pressure to said fluid motor whereby the fluid motor is operated by said fluid under pressure.

25 18. The combination of a work member adapted to encounter a variable resistance in its work, a prime mover, connections between the prime mover and the rotary work member whereby the prime mover may rotate the work member, said connections embodying fluid pressure generating means acting to build up a fluid pressure dependent upon the resistance encountered by the work member in its work, means for regulating the feed of the work member with respect to its work, a fluid motor controlling said last mentioned means, and connections from said fluid under pressure to said fluid motor whereby the fluid motor is operated by said fluid under pressure, and an adjustable reduction valve in said last mentioned connections.

19. The combination of a work member adapted to encounter a variable resistance in its work, a prime mover, connections between the prime mover and the work member whereby the prime mover operates the work member, said connections including a fluid pump acting to build up a fluid pressure dependent upon the resistance encountered by the work member, and means for adjusting the stroke of said pump to vary the said fluid pressure independently of the resistance encountered by the work member and means for regulating the feed of the work member with respect to its work responsive to variations in said fluid pressure.

20. The combination of a rotary cutting member, a driving shaft, a hydraulic pump connected to be driven by said shaft, a shaft driven by the hydraulic pressure built up by said pump and connections whereby the last mentioned shaft drives the cutting member, and means whereby increases in said hydraulic pressure tend to decrease the load encountered by the cutting member.

21. The combination of a rotary drill device, a prime mover, transmission means connecting the prime mover and drill device, said transmission means including two rotatable elements adapted to rotate with respect to each other, and a fluid pressure generator connecting said elements, and means whereby the feed of the drill is controlled by the slip between the elements.

In testimony whereof I have signed my name to this specification.

LOUIS H. THULLEN.
